UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

SOLE-LAYING MACHINE.

Application filed March 22, 1919. Serial No. 284,377.

To all whom it may concern:

Be it known that I, ERASTUS E. WINKLEY, a citizen of the United States, residing at Lynn, in the county of Essex and 5 State of Massachusetts, have invented certain new and useful Improvements in Sole-Laying Machines; and I do hereby declare the following to be a full, clear, and exact description of the invention, such as will 10 enable others skilled in the art to which it appertains to make and use the same.

This invention relates to a machine for performing the operation known as sole laying in the manufacture of McKay shoes, 15 and shoes in which the outer sole is secured to the shoe by pegs or nails.

In the manufacture of the above class of shoes, the sole is adjusted upon the lasted shoe in the desired position and is secured 20 in place preparatory to the sewing, pegging or nailing operation by a few tacks or nails, which are driven through the sole at the toe and heel of the shoe and hold the sole in place during the operation of securing it 25 to the shoe. A machine having means for adjusting the toe end and forepart of a sole in the desired position with respect to the upper of a lasted shoe, and for securing said portion to the shoe in adjusted position, is 30 disclosed in Letters Patent No. 1,081,355, granted to the applicant on Dec. 16, 1913. After the sole has been thus located and temporarily secured in place at the toe and forepart of the shoe, it is desirable, because 35 of the flexibility of the unsecured shank portion of the sole to center the heel seat end thereof upon the bottom of the shoe before securing it in place. The adjusting of the heel-seat end of the sole, relatively 40 to the shoe, has heretofore been accomplished entirely by hand, requiring considerable skill and care on the part of the operator and even then the soles were liable to be inaccurately centered.

45 One of the objects of the present invention is to provide a sole laying machine for shoes of the above class which is of simple and compact construction and by means of which both ends of the sole may be located 50 and secured in place upon the shoe, in the same machine. In this manner the necessity of performing by hand one of the steps in the sole laying operation is avoided, the complete operation is performed more

quickly and the soles are uniformly located 55 upon different shoes.

With this object in view, one feature of the present invention consists in the provision, in a unitary structure, of closely adjacent nail driving mechanisms and a sole 60 locating device disposed in working relation to each nail driving mechanism, one of said locating devices being adapted to operate upon the toe end of a shoe presented thereto, to relatively locate the sole and the upper, 65 and the other locating device being adapted to operate upon the heel end of the shoe, subsequently presented thereto, to center the heel seat end of the sole with respect to the upper. 70

In performing the sole laying operation it is desirable that the nail driving mechanism shall drive a single nail only, at each operation thereof, when either the toe or heel end of a shoe is first presented to the 75 machine. After the sole has been secured at the toe or heel of the shoe against accidental displacement, by means of a single nail, it is customary to drive several nails along the marginal portion of the forepart 80 or heel end of the sole as the case may be, at either side. In the machine of the patent referred to, a single nail only is driven for each depression of the treadle by the operator. In said machine after the first securing 85 nail has been driven, the sole adjusting mechanism is withdrawn from working relation with the nail driving mechanism so that the operator may freely manipulate the shoe to position it to receive the succeeding 90 nails, which are then driven in the same manner as the first nail, a separate depression of the treadle being required to effect the driving of each nail. Inasmuch as these 95 nails are to be located in a row on each side of the sole, the operator can easily manipulate the shoe to receive the nails more rapidly than they can be driven when the nail driving mechanism is stopped between 100 the driving of each nail, and it will therefore be seen that the process of driving the succeeding securing nails is unnecessarily delayed, in the machine of the above mentioned patent, and that the operator is obliged to perform a considerable amount 105 of unnecessary labor in repeatedly depressing the treadle.

Another object of the invention is to im-

prove the mechanism for controlling the nail driving operation, so that a single nail only will be driven when the shoe is engaged by either of the locating devices, but thereafter when the locating device has been withdrawn, a series of nails may be driven in rapid succession with a minimum amount of effort on the part of the operator.

In accordance with this object, another feature of the invention contemplates the provision of means for causing the withdrawal of the locating device which is in engagement with the shoe and the automatic stopping of the active nail driving mechanism after the first securing nail has been driven, and means operated by the withdrawal of either locating device to prevent the automatic stopping of the associated nail driving mechanism, while said device remains in withdrawn position, so that when either locating device is in working relation with a nail driving mechanism, a single nail only will be driven for each depression of the treadle, and when said locating device is withdrawn an intermittent series of nails will be driven so long as the treadle is kept depressed.

The invention further consists in other novel features of construction, combinations and arrangement of parts hereinafter described and claimed, the advantages of which will be apparent to those skilled in the art from the following description.

In the accompanying drawings illustrating the preferred embodiment of the invention, Figure 1 is a view in side elevation of the machine; Fig. 2 is a view in front elevation of a portion of the machine, parts of the right hand nail driving mechanism being omitted; Fig. 3 is a fragmentary view partly in side elevation and partly in section of the machine, showing the locating device for the heel end of the shoe in working relation with its associated nail driving mechanism and locating a sole in position to receive a securing nail at the heel; Fig. 4 is a top plan view of the machine; Fig. 5 is a detail view partly in plan and partly in section, illustrating particularly the positioning device for the heel end of the shoe and the means for automatically controlling the starting and stopping of the nail driving mechanism; Fig. 6 is a detail view in rear elevation, on an enlarged scale, showing the locating device for the heel end of a shoe; Fig. 7 is a detail view showing a section on the line 7—7 of Fig. 6; and Figs. 8, 9 and 10 are detail views showing the starting and stopping mechanism for the nail driving devices and part of the automatic controlling means therefor.

In the illustrated embodiment of the invention the two nail driving mechanisms, which are indicated at 12 and 14, correspond in construction to the nail driving mecha-

nism which is illustrated and described in the Patent No. 1,081,355, previously referred to, and are similar to the corresponding mechanisms of well known machines commonly employed for laying the soles of McKay shoes. The nail driving mechanisms 12 and 14 are supported upon similar upright extensions 16 and 18 of a standard 20, upon which the other operating parts of the machine are mounted. The two locating devices, one of which acts upon the toe end of the shoe and the other upon the heel end thereof, relatively to position the sole and the upper, are indicated generally at 22 and 24 respectively. The locating device 22 is carried upon a support 26 which is pivotally mounted, at its lower end on a bracket 28 that is secured to the standard 20. The locating device 22, together with its support 26, is identical in construction, arrangement and mode of operation with the locating device and the support therefor which is illustrated and described in the patent referred to, and the same provision is made for holding it in working relation with the nail driving mechanism and withdrawing it therefrom, as in said patent.

In performing the sole laying operation by means of the present machine, the toe end of the shoe with the sole held against the bottom thereof by the operator, is first presented to the locating device 22, and the forepart of the sole and upper are relatively positioned in the same manner as described in the above mentioned patent. Thereafter, upon the depression of a treadle 30, the shoe is securely clamped in position for the nail driving operation by means of mechanism associated with the locating device 22, and a single securing nail is driven, after which the nail driving mechanism is automatically stopped, and the device 22 is withdrawn from the shoe, all as set forth in said patent.

In the present construction, however, when the treadle is again depressed to start the nail driving mechanism, the nail driving operation continues intermittently so long as the treadle is kept depressed and the succeeding securing nails are driven in rapid succession without further action on the part of the operator other than manipulating the shoe so that the nails will be driven in the desired positions along the marginal portion of the forepart of the shoe. In order that a series of nails may thus be successively driven, controlling means is provided, which is rendered operative by the rearward movement of the support for the locating device 22, and serves to prevent the automatic stopping of the nail driving mechanism. This controlling means is identical in construction and mode of operation with the means employed for preventing the automatic stopping of the nail driving mechanism 14, which operates upon the heel

end of the shoe, and the description, herein-after contained, of the latter mechanism will suffice for both. After the desired number of nails have been driven properly to secure 5 the forepart of the sole in place, the nail driving operation is stopped by the release of the treadle 30 and the operator is ready to present the heel of the shoe to the locating device 24, in order that the heel seat end 10 of the sole may be centered upon the bottom of the shoe and the shoe so located with respect to the nail driving mechanism 14 that the first securing nail will be driven approximately on the medial line of the sole 15 and at the proper distance from the rear edge thereof.

By reason of the juxtaposition of the two sets of locating devices 22 and 24, the positioning of the shoe for the operations to be 20 performed upon it after the sole has been located and secured at the toe end of the shoe, may be conveniently accomplished by the operator merely by turning, end for end, the shoe which he is holding, and then presenting it to the device 24. As already stated, it has heretofore been the practice to adjust the heel-seat end of the sole by hand, after the toe end of the sole has been located, and secured in place. In this way the accuracy 25 of the operation is dependent entirely upon the skill of the operator and the soles are liable to be non-uniformly located at the heel end thereof, upon different shoes. Moreover such a method involves additional 30 handling of the shoe and unnecessarily delays the sole laying operation. It will be apparent that the above disadvantages are obviated by means of the present machine with its closely adjacent arrangement of the 35 locating devices.

In order to permit the locating device 24 for the heel end of the shoe to be swung into and out of working relation with the nail driving mechanism 14, said locating device 40 is carried upon a support 32 which is bifurcated at its lower end, as indicated in Fig. 2, and is pivotally mounted on pivots 34 between two arms of a bracket 28 on the standard 20. The support 32 is held in working 45 relation with the nail driving mechanism 14 by means of a toggle comprising links 36 and 38 (Figs. 1 and 3) which are connected by a pivot 40. The arms of the link 38 are pivoted at their rear ends upon a pivot pin 50 55 42 which extends through a bracket on the extension 18 of the standard 20 and the two side members of the link 36 are pivotally connected at their forward ends, with the support 32 by pivot screws 44. A shaft 46 60 (Fig. 3) is mounted in the side members of the link 36, and carries a trip lever 48 between said side members. The under side of the lever 48 at the rear of the shaft 46 is arranged to engage a stop 50 on the link 36, 65 and the upper side of the lever at the rear

of the stop 50 is arranged to be engaged by an adjustable stop screw 52 carried by the link 38 and arranged in front of the pivot 40. The trip lever 48 and the stops 50 and 52 thus form stop devices for limiting the 70 downward movement of the pivot 40 of the toggle when the toggle is straight, so that the toggle will act as a brace to hold the support 32 in working relation with the nail driving mechanism 14 against tension of 75 springs 54 which tend to swing the support rearwardly and thus move the locating device 24, carried on its upper end, out of working relation with the nail driving mechanism. The means just described is 80 similar to the means employed for a like purpose in the machine of the patent herein-before referred to.

The centering of the sole at the heel of the shoe is accomplished by means of the 85 locating device 24 which is mounted upon a head 56 (Figs. 2 and 6) at the upper end of the support 32, and comprises a pair of centering gages 58 arranged to embrace the heel end of the upper, and a pair 90 of centering gages 60 arranged to embrace the heel end of the sole, when the shoe is presented to the device by the operator. On each of the gages 60, above the face which engages the edge of the sole, is 95 formed an inwardly projecting lip 62, which is adapted to engage the top of the sole and maintain the edge thereof in alinement with the face of the gage. When the sole is pressed upwardly 100 against the lips 62 by the operator, its upper surface is maintained by means of the lips in perpendicular relationship with the nail throat of the nail driving mechanism. A back rest 64 (Fig. 5) is 105 provided against which the shoe is held during the driving of the first securing nail and which serves to locate the shoe longitudinally with respect to the nail throat.

In order that the two pairs of centering 110 gages 58 and 60 may act uniformly to position the heel ends of the uppers and soles, respectively, of different shoes, and may also automatically accommodate themselves to variations in the widths of different uppers 115 and soles respectively, the individual members of each pair of centering gages are held yieldingly in position and are connected to move in unison. In the construction shown, the centering gages 58 and 60 are in the form of levers, the front ends of which are shaped to engage the opposite sides of the heel end of a shoe upper and sole, respectively, and the rear ends of which are pivotally supported upon the pivots 63. 120 The gages 58 are connected to move concurrently by intermeshing segments 66, formed on their rear ends, and are held yieldingly in position by a spring 68. The gages 60 are arranged to move independ- 125

ently of the gages 58 and are connected to move together by intermeshing segments 70, formed on their rear ends, and are held yieldingly in position by a spring 72.

5 To avoid excessive movement of the yielding centering gages 58 and 60 in introducing the upper and sole, means are provided for varying the distance between the opposing gage levers when in their normal 10 position. This means, in the construction shown, consists of an adjusting lever 74 (Figs. 2, 3, 6 and 7) which is fulcrumed on a stud 76 that is carried by the head 56. An arm 78 on one of the gages 60 is held by 15 means of the spring 72 in engagement with the upper end of the lever 74 and an upstanding lug 80 which projects from the rear of one of the levers 58 is held by means of the spring 68 in engagement with a lug 20 82 projecting rearwardly from the corresponding lever 60. With this construction, when the adjusting lever 74 is operated by means of a handle 84 that is formed at its lower end, the spaces between the opposing 25 surfaces of the gages 58 and 60 may be varied. A spring-pressed detent 86 which is pivotally mounted on the handle of the lever 74 and arranged cooperatively to engage one of a series of notches in a disk 30 88 that is fixed to the stud 76, serves to lock the lever 74 in its adjusted position and determine the normal positions of both sets of gages.

The centering of the heel end of the sole 35 with respect to the upper is accomplished by introducing the shoe between the opposing centering gages 58 and 60. The shoe is pressed upwardly by the operator so that the bottom of the sole is kept in 40 contact on both sides with the overlying lips 62 on the gages 60, and is advanced between the gages until the heel end of the shoe engages the back rest 64. The centering gages and the back rest are so arranged, 45 with respect to the nail driving mechanism, when they are in working relation with the latter, that the heel end of the shoe is properly positioned to receive the first securing nail. The lips 62, on the gages 60, by engagement with the bottom of the sole, determine the transverse angular position of the shoe so that the nails will be driven perpendicularly through the sole.

50 The nail driving mechanism 14 is driven by means of a belt 90 (Fig. 4) which passes over a loose pulley 92 on the main shaft 94 thereof, and over one face of a pulley 96, that is loosely mounted on the main shaft of the nail driving mechanism 12 and is continuously driven from a suitable source of power by means of a belt 98 which passes over another face of said pulley. In order that only a single securing nail may be driven when the locating device 24 is in 55 working relation with the nail driving mech-

anism, it is preferred to employ a starting and stopping mechanism of the character illustrated in Figs. 3, 8, 9 and 10. As shown in these views the pulley 92 constitutes one member of a friction driving clutch for the 70 nail driving mechanism. The other member of the clutch is indicated at 100, and the clutch members are adapted to be engaged by the downward movement of an operating wedge 102, which is bifurcated to straddle 75 the main shaft 94, and to be disengaged upon an upward movement thereof. The operating wedge 102 is carried by the upper end of a frame 104, the lower end of which is provided with a sleeve 106 surrounding an operating rod 108 and guided in a bearing 110 in a bracket 112 that is secured to the extension 18 of the standard 20. The operating rod 108 is connected by means of a link 114 (Fig. 1) to a treadle 116 which is pivotally mounted at 118 (Fig. 1) on the base of the standard 20 and is normally held in raised position by a spring 120. A spring 122 is interposed between a collar 124 on the operating rod 108 and the lower end of the 90 sleeve 106, and tends to force the wedge carrying frame 104 upwardly with relation to the operating rod. The frame 104 carries a roll 126 near its upper end, which is arranged to ride against a cam 128 on the driving shaft of the nail driving mechanism. 95

When the parts are in the position for depressing the treadle and starting the machine, as shown in Figs. 1 and 2, the lower part of the cam 128 is above the roll 126, and the frame 104 and the rod 108 are locked together by a latch 130 which is pivoted on the frame, and is so arranged that its upper end engages a collar 132 on the rod 108, as indicated in Fig. 8. Now when the treadle 105 116 is depressed, the frame 104 is drawn down with the rod 108 so that the wedge 102 effects the engagement of the members of the driving clutch, the driving shaft 94 is rotated and a single nail is driven. Immediately after the driving shaft 94 starts to rotate the high part of the cam 128 rides over the roll 126 so that the frame 104 is prevented from rising until after the nail driving operation is completed. Immediately 110 after the cam 128 thus locks the frame 104 in its depressed position, the high part of the cam rides against a roll 134 on the upper end of a bell crank lever 136 which is pivoted on the frame 104, rocking the lever about its pivot. This movement of the lever forces downward a rod 138 which is pivotally connected with the lower end of the lever and has its lower end arranged to be normally held in engagement with a shoulder 140 on the latch 130 by means of a spring 142 which connects the rod and the bell crank lever in such a manner that it also serves to hold the roll 134 on the lever 136 against the cam 128. The latch 130 is thus 120 125 130

disengaged from the collar 132 and the continued downward movement of the rod 138 carries a cam surface 144 on the rod against the latch so that the lower 5 end of the rod is disengaged from the shoulder 140. As soon as the high part of the cam 128 passes beyond the roll 126, the frame 104 is moved upwardly by the spring 122, raising the wedge 102 so that the clutch is disengaged.

Before the nail driving mechanism can be again thrown into operation, the treadle 116 must be released. When the treadle 116 is released the rod 108 moves upwardly into 15 the position indicated in Fig. 8, and the latch 130 again engages the collar 132 on the rod, locking the frame 104 and the rod 108 together so that the frame will be drawn down upon the succeeding depression of the 20 treadle. As thus far described, the construction and arrangement of the operating wedge 102, the wedge carrying frame 104 together with the associated parts, and the manner in which they are operated is similar 25 to the construction, arrangement and mode of operation of like parts in the patent previously referred to.

After the heel end of the sole has been located and secured against accidental displacement by the driving of a single securing nail at the end of the heel, the locating device 24 is automatically withdrawn, leaving the space below the nail driving mechanism unobstructed in order that the 30 shoe may be readily manipulated by the operator in the usual manner while the succeeding securing nails are being driven along the marginal portions of the rear part of the sole.

40 In the construction shown, means is provided for breaking the toggle which holds the support 32 in its advanced position, upon the releasing of the treadle 116, so that the support and the locating devices carried thereby are automatically swung back out of the way by the springs 54. The means for thus breaking the toggle is similar to corresponding means which is described in the patent referred to, and comprises a dog 45 146, (Figs. 1, 2 and 3) arranged to operate upon the forward end of the tripping lever 48. The dog 146 is pivoted on a sleeve 148 which is secured near the upper end of a rod 150 which extends through bearings 152, that are formed near the upper and lower 55 ends of the support 32, and is pivotally connected by a pin and slot connection 154 to the rear end of a lever 156 which is fulcrumed at 158 in the bracket 28. The forward end of the lever 156 is connected by means of a link 160 with the treadle 116. The dog 146 is held yieldingly in position with its lower end projecting, as indicated in Fig. 3, by a spring surrounding its pivot. 60 When the treadle 116 is depressed to start

the nail driving mechanism for the purpose of driving the first securing nail in the heel portion of the sole, the rod 150 is raised and the dog 146 rides idly up past the end of the trip lever 48. When the treadle 116 is released and the rod 150 moves downwardly, the dog 146 strikes the front end of the trip lever 48, rocking it on its pivot so that the rear end of the lever, acting upon the stop screw 52, forces the front end of the link 38 70 of the toggle upwardly, thus breaking the toggle so that the spring 54 acts quickly to swing the support 32 back towards the standard 20, as shown in Fig. 1. This movement of the support withdraws the locating device from the shoe, which is left in the hands of the operator in position for further manipulation in positioning it for driving the succeeding securing nails.

80 After the locating device has been withdrawn, the operator again depresses the treadle 116 and starts the nail driving mechanism for the purpose of driving the succeeding nails which are to secure the heel seat and shank portion of the sole in place.

85 During the driving of these nails, the shoe being supported only by means of the operator's hands, may be readily manipulated so that the nails may be driven in the desired locations in the sole. In order that the nails may be driven rapidly, it is desirable that the nail driving mechanism shall now be operated to drive a series of nails successively by means of a single depression of the treadle. To this end means is provided 90 which operates automatically when the locating devices are withdrawn, to throw the latch release rod 138 out of operative engagement with the latch 130, and which holds the rod away from the latch so long as the treadle remains depressed, and the locating devices are allowed to remain in withdrawn position.

95 The means for rendering the latch release rod inoperative consists of a curved lever 162 (Figs. 8, 9 and 10) which is pivoted at 164 on the wedge carrying frame 104 and is operatively connected with the support 32 by means of a link 166, which has, at its upper end, a universal joint connection 168 with the lever 162, a bell crank lever 170, which is fulcrumed at 172 in a bracket on the standard 20 and one arm of which is connected by a universal joint 174 with the lower end of the link 166, and a link 176 which connects the other arm of the bell crank lever 170 with the support 32 at 178.

100 110 115 120 125 130 The lever 162 is arranged to be swung downwardly by means of the connections just described, when the support is withdrawn to throw the latch release rod 138 out of operative relation with the latch 130. For this purpose the lever 162 carries a roll 180 at its free end which projects through a slot 182 in the frame 104 and is adapted to

engage the rod 138, as the lever 162 is swung downwardly, and move the rod so that its lower end will be clear of the shoulder 140 on the latch 130, as shown in Fig. 8. The 5 rod 138 will thus be held inoperative and will reciprocate idly so long as the support 32 is permitted to remain in its rearward position, and the latch 130, remaining in engagement with the collar 132, the nail driving 10 operation will continue intermittently so long as the operator keeps the treadle depressed. After the required number of nails have been driven, the treadle is released and as it is raised by the spring 120, the wedge 15 carrying frame 104 is also raised and the clutch is disengaged so that the nail driving 20 operation is stopped.

When another sole is to be operated upon by the nail driving mechanism 14, the support 20 32 is drawn forward into the position indicated in Fig. 3; thus straightening the toggle which acts to hold the locating device 24 in working relation with the nail driving mechanism 14. For convenience in 25 drawing forward the support 32, handles 184 are provided upon the side members of the link 36 of the toggle, below the pivotal connections between the link and the support 32.

30 It will be seen that by providing, in a single machine, means for locating the heel end of a sole, as well as the toe end thereof, relatively to the shoe, the entire sole laying operation may be performed by the operating 35 instrumentalities of the machine, as the shoe is presented thereto by the operator, and the operation is consequently performed more accurately and quickly than heretofore.

While it is preferred to embody the invention 40 in a machine having the specific construction and arrangement of parts herein shown and described, it will be understood that such construction and arrangement are not essential except so far as specified in the 45 claims and may be modified without departing from the spirit and scope of the invention.

Having described the invention, that which is claimed as new is:—

50 1. A shoe machine having, in combination, a device for locating or positioning an article in a predetermined manner and adapted for withdrawal from the article operated upon after it has performed its locating function, 55 and nail driving mechanism arranged to drive a single nail into the article when the locating device is in operative position and automatically to drive a series of nails into the article when the locating device is withdrawn.

60 2. A sole laying machine having, in combination, a device for locating a sole on the bottom of a shoe adapted to be withdrawn from the shoe after it has performed its locating function, and nail driving mechanism

arranged to drive a single securing nail through the sole when the locating device is in operative position and automatically to drive a series of nails therethrough when the locating device is withdrawn. 70

3. A sole laying machine having, in combination, a device arranged to locate a sole on the bottom of a shoe and adapted to be therewithdrawn from the shoe, nail driving mechanism, means arranged to operate automatically when the locating device is in operative position to stop the nail driving operation after a single nail has been driven, and means actuated by the withdrawal of the locating device for preventing the automatic 80 stopping of the nail driving mechanism. 75

4. A machine having, in combination, nail driving mechanism, a device for locating an article in a predetermined position with respect to the nail driving mechanism, and controllable means for causing the latter to drive a single nail or a series of nails. 85

5. A shoe machine having, in combination, a device for locating an article in a predetermined manner and adapted to be withdrawn from the article operated upon after it has performed its locating function and a nail driving mechanism arranged to drive automatically a series of nails into the article only when the locating device is 95 withdrawn. 90

6. A sole laying machine having, in combination, a device for adjusting a sole on the bottom of a shoe in position to be secured thereto, nail driving mechanism, and controllable means for causing a series of 100 nails to be driven to secure the sole in adjusted position. 100

7. A machine of the class described having, in combination, fastening inserting means, a treadle for initiating operation of the machine, and means arranged so that displacement of the treadle will alternatively cause the machine either to operate to drive a single fastening or to continue to drive fastenings as long as the treadle remains displaced. 105

8. A machine of the class described having, in combination, means for operating upon shoes, a gage for locating the shoes in a predetermined position with respect to the operating means, and means operable alternatively for causing the operating means to operate through a single cycle of operation and then to come to rest or to operate through a series of cycles of operation. 115

9. A machine of the class described having, in combination, means for relatively positioning a plurality of shoe parts, means for operating upon the shoe parts, and controlling means for the operating means arranged to cause the machine to operate through a single cycle of operation and then to come to rest when operation of the ma- 125 130

chine is initiated with the positioning means in operative position and to cause the machine to operate through a series of cycles of operation when operation of the machine 5 is initiated with the positioning means out of operative position.

10. A fastening inserting machine having, in combination, means for inserting fastenings, a clutch arranged to transmit power 10 for the operation of the machine, clutch controlling mechanism including a latch arranged by its displacement to cause the clutch to be thrown into inoperative condition, and means operable alternatively to 15 cause the latch to be thrown out of operative position before the completion of the first cycle of operation when the machine is started or to cause the latch to remain in operative position during a series of cycles 20 of operation.

11. A machine of the class described having, in combination, work positioning means

movable to operative and inoperative positions, a clutch for controlling the performance of an operation upon the work, clutch 25 controlling means including a latch arranged when in operative position to permit the machine to operate through a series of cycles of operation and when moved to inoperative position to cause the machine to 30 come to rest at the conclusion of the cycle of operation during which it is moved, and connections from the positioning means to the latch to cause the latch to be moved to inoperative position before the conclusion 35 of the first cycle of operation when the machine is started with the positioning means in operative position and to cause the latch to remain in operative position to permit the machine to operate through a series of 40 cycles of operation when the machine is started with the positioning means out of operative position.
